UNITED STATES PATENT OFFICE.

EDWARD WESTERVELT LAWSON, OF WEST PALM BEACH, FLORIDA.

DESIGN FOR A WEATHER VANE.

Application filed July 17, 1928 Serial No. 27,509. Term of patent 7 years.

To all whom it may concern:

Be it known that I, EDWARD WESTERVELT LAWSON, a citizen of the United States, and a resident of West Palm Beach, in the county of Palm Beach and State of Florida, have invented a new, original, and ornamental Design for a Weather Vane, of which the following is a specification, reference being had to the accompanying drawing, forming part thereof.

Figure 1 of the drawing represents a front elevation of a weather vane showing my new design; and

Fig. 2 is a side elevation thereof.

I claim:

The ornamental design for a weather vane as shown.

EDWARD WESTERVELT LAWSON.
